Primary Examiner — Marie D. Fast Horse(74) *Attorney, Agent, or Firm* — Henry M. Feiereisen LLC(57) **CLAIM**

The ornamental design for a monitor for data processing device, as shown and described.

DESCRIPTION

FIG. 1 is a front view of a monitor for data processing device, showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a top, front and left side perspective view thereof; and,

FIG. 8 is a top, rear and right side perspective view thereof.

1 Claim, 8 Drawing Sheets(56)
